(57) **CLAIM**

The ornamental design for a display screen with icon, as
shown and described.

DESCRIPTION

FIG. 1 is a front view of a display screen with icon according
to a first embodiment of the claimed design.

FIG. 2 is a front view of the display screen with icon of FIG.
1 shown on a monitor.

FIG. 3 is a rear view of the monitor of FIG. 2.

FIG. 4 is a left side view of the monitor of FIG. 2.

FIG. 5 is a right side view of the monitor of FIG. 2.

FIG. 6 is a top view of the monitor of FIG. 2.

FIG. 7 is a bottom view of the monitor of FIG. 2.

FIG. 8 is a front view of a display screen with icon according
to a second embodiment of the claimed design; and,
FIG. 9 is a front view of the display screen with icon of FIG.
8 shown on a monitor.

The dash-dot broken lines showing the display screen or
portion thereof in FIGS. 1-2 and 8-9 define the boundary of
the claimed design and form no part of the claimed design.
The dash-dash broken lines showing portions of the icon in
FIGS. 1-2 and 8-9 illustrate portions of the display screen
with icon that form no part of the claimed design.

The dash-dot-dot broken lines showing the monitor in FIGS.
2-7 and 9 illustrate an example use environment of the
display screen with icon and form no part of the claimed
design.

The rear view, left side view, right side view, top view, and
bottom view of the monitor of FIG. 9 is the same as shown
by FIGS. 3, 4, 5, 6, and 7, respectively.

1 Claim, 9 Drawing Sheets
